EXPANDABLE MANDREL FOR MOUNTING
ARMOR ROD TOOLSHarter C. Enders, Wabeno, Wis., assignor of one-half to
Angus H. Beaton, Oconto, Wisconsin

Application July 1, 1955, Serial No. 519,330

3 Claims. (Cl. 57—10)

This invention relates generally to tools for applying armor rods to energized conductors, and more particularly to an expandable mandrel or mounting tool accessory thereto, for temporarily uniting pairs of armor tools in rigid assembly for convenience in initially placing a pair of loaded armor rod tools on a conductor to be armored.

The purpose of this invention is to eliminate the tool instability and unsteadiness attending the initial placing and mounting of the paired armor rod tools on a conductor; and to contribute to electrical safety.

In the usual process of mounting loaded armor rod tools on a conductor, the tools and rods become longitudinally displaced and disarranged, relative to each other, resulting from the efforts to place the loaded armor tools on a conductor, and from the clamp stick manipulation to draw the two tool frame halves against each other.

This invention prevents the suitably spaced tools and prearranged rods from sliding out of predetermined assembly while the loaded tools are lifted and mounted on the energized conductor.

An object of this invention is the provision of an accessory tool for placing paired armor rod tools on an energized conductor.

Another object is to provide means for releasably uniting spaced armor rod tools.

Yet another object of this invention is the provision of expandable means for releasably uniting spaced armor rod tools.

Still another object is to provide expandable mandrel means for releasably uniting spaced armor rod tools.

Another object is to provide means for lifting and placing loaded armor rod tools on an energized conductor, controllable by a single man, thereby enhancing safety and efficiency.

A further object of this invention is the provision of a balanced expandable mandrel construction having centrally located actuating means externally actuatable.

Other specific objects and many of the attendant advantages of this invention will be readily appreciated as the same becomes better understood by reference to the following detailed description when considered in connection with the accompanying drawings in which like reference numerals designate like parts throughout the figures thereof and wherein:

Fig. 1 is a perspective view showing a pair of conventional armor rod tools, mounted on an expandable mandrel which forms the gist of this invention.

Fig. 2 is a side elevation view of the expandable mandrel, per se, shown in Fig. 1.

Fig. 3 is an end elevation view of Fig. 2; and

Fig. 4 is a side elevation of the eye bolt, per se, shown in Figs. 2 and 3.

Referring now to the drawings, wherein like reference characters designate like or corresponding parts throughout the several views, there is shown in Fig. 1 an associated pair of conventional armor rod wrapping tools, shown in dotted lines, consisting of hinged complementary half frames 10—11, and 12—13, having a centrally

2

disposed conductor receiving opening, surrounded by a plurality of armor rod receiving openings in circumferential spaced relation.

Some means are usually provided on said frames for conveniently effecting a rotation of the frames. Such means usually project from said frames and are adapted to be engaged by an insulated disconnect stick for holding the frame in a fixed position or for rotating the frame to wind armor rods on an energized conductor, said latter means comprising one or more radially projecting arms each provided with a stick receiving eye 14 in its end portion.

Said eye openings 14 can also serve as receiving means for an expandable mandrel or mounting tool which when inserted forcibly in an eye opening will support the armor rod tools thereon while said armor rod tools are being placed on the conductor to be armored. It is this expandable mandrel which forms the present invention.

The body of the expandable mandrel comprises a tubular element divided longitudinally into two half segments 15 and 16, oppositely disposed and confronting each other. These segments are provided with reduced diameter end portions 17—18, and 19—21, to be loosely received in eye openings 14. The shoulders 22—23 and 24—25, resulting from the diameter reduction, function as spacing abutments to suitably space the armor rod tools on the expandable mandrel.

The upper segment 15 is provided with a centrally located nut 26 welded on the outer periphery, and aligned with a similarly threaded bore 27 through the segment wall, to receive threaded eye bolt 28.

The lower segment 16 is provided with a centrally located deck plate 29 welded horizontally across the concave wall thereof. Said deck plate is centrally apertured, and aligned with the threaded bores of nut 26 and upper segment wall bore 27, to receive the reduced diameter end portion 31 of the eye bolt 28. The shoulder resulting from said diameter reduction is juxtaposed against the deck plate and the protruding reduced diameter portion 30 is peened at 32, thereby forming a swivel connection between the end of the eye bolt and the fixed deck plate.

Operation: The procedure for applying the expandable mandrel tool to a pair of associated armor rod tools, follows.

The segments 15 and 16 are oppositely disposed relatively parallel, and the eye bolt turned until the segments are brought into close contact with each other, thereby forming a closed tubular member.

The reduced diameter portion 17—18 is then inserted in an eye 14 of a conventional armor rod tool.

The other reduced diameter portion 19—21 is then inserted in an eye 14 of an associated armor rod tool similarly oriented.

With the associated armor rod tools thus mounted on the mandrel segments, the eye bolt 28 is turned so as to separate the segments and expand the mandrel forcibly against the inner periphery of the eye openings, thereby uniting the paired armor rod tools in rigid assembly.

The rigid assembly can now be loaded with armor rods. The loaded unitary assembly is now mounted on a standard clamp stick, the clamp stick engaging the eye 33 of the eye bolt 28.

The clamp stick is a common tool in a lineman's kit. The clamp sticks in question are preferably of the type having a long pole of wood or other insulating material for mounting a clamp stick head. The eye 33 is drawn into and fixedly secured in the clamp stick head and supported thereby.

The unit thus supported is lifted by the clamp stick and applied to the energized conductor.

While the unit is thus rigidly held in place on the conductor to be armored, a second clamp stick engages eye

bolt 34 on the armor rod tools, thereby driving the two complementary frame halves against each other to close the frames around the conductor.

With the paired armor rod tools firmly mounted on the conductor, the mandrel may be removed from the paired armor rod tools by rotating the eye bolt, by means of the clamp stick, so as to draw the mandrel segments together, thereby collapsing the mandrel. In its collapsed condition the mandrel ends can be easily removed from the armor rod tool eyes 14.

Thereupon one operator may take a disconnect stick, a common tool in a lineman's kit, and engage it in an eye 14 in one of the arms of one frame, to hold that tool in fixed position. The other operator may then engage his stick in an eye 14 in the other associated frame or tool, and may push or pull as the case may be to rotate said other frame and twist the armor rod about the energized conductor.

The frames are alternately held and rotated until the frames progress to the ends of the armor rods, which have been tightly wrapped and wound around the conductor.

The frames are then removed by means of a clamp stick applied to eye bolts 34, operative to open the frames, and allow them to be lifted from the conductor.

It will be thus observed that the present invention comprises an expandable mandrel adapted for use in combination with conventional armor rod tools.

The characteristic features of this invention are the combination of an expandable mandrel with a pair of associated armor rod tools mounted thereon; an expandable mandrel having centrally located expanding means; an expandable mandrel having reduced diameter end portions; and a balanced expandable mandrel design adapted for use with a pair of associated armor rod tools.

Obviously many modifications and variations of the present invention are possible in the light of the above teachings. It is therefore to be understood, that within the scope of the appended claims, the invention may be practiced otherwise than as specifically described.

What is claimed and desired to be protected by Letters Patent of the United States is:

1. An expandable mandrel, comprising: a pair of substantially similar elongated members oppositely and parallelly related; and a bolt substantially normally related thereto, threadedly engaged through one of said members and swivelly engaged with the other of said members, said elongated members having reduced end portions to provide abutment shoulders.
- 10 2. An expandable mandrel, comprising: a pair of substantially similar elongated members oppositely and parallelly related, the outer surfaces of the end portions of said members being curved; and a bolt normally related to said members, threadedly engaged through one of said members intermediate the ends thereof and swivelly engaged with the other of said members, said elongated members having reduced end portions, conforming substantially to the curvature of said outer surfaces, to provide abutment shoulders.
- 20 3. An expandable mandrel, comprising: a pair of elongated similar substantially semi-cylindrical segments oppositely and parallelly related; and an eye bolt normally related to said segments, threadedly engaged substantially through the center of one of said segments and swivelly engaged with the other of said segments, and similar reduced diameter end portions on said semi-cylindrical segments providing abutment shoulders substantially equally spaced from the ends of said segments, respectively.
